UNITED STATES PATENT OFFICE.

ALFRED B. GOODRICH, OF BUFFALO, NEW YORK, ASSIGNOR OF ONE-HALF
TO WILLIAM J. BEYER, OF SAME PLACE.

WATCHMAN'S TIME-RECORDER.

SPECIFICATION forming part of Letters Patent No. 261,149, dated July 18, 1882,
Application filed April 3, 1882. (No model.)

To all whom it may concern:

Be it known that I, ALFRED B. GOODRICH, a citizen of the United States, residing at Buffalo, county of Erie, and State of New York, have made certain Improvements in Night-Watchmen Detectors, of which the following is a specification.

This device is for the purpose of insuring that night-watchmen in factories, hotels, manu-
10 factories, &c., make a periodical visit to each and all rooms or stories in such buildings, and record the time of visit on a device provided for that purpose, so that in the morning the proper person can discover if the watchman has prop-
15 erly performed his duties. Such devices are already in use, but are somewhat expensive and complicated.

My invention consists in its simplicity, but mainly in utilizing the usual speaking-tubes
20 running through the different rooms or stories of a building and connecting therewith a sim-
ple recording device, which by merely using these tubes pneumatically (blowing therein) will make such record by a pen, pencil, or
25 pricking-point striking a roll of paper moved by clock-work, all as hereinafter fully ex-
plained.

In the drawings, Figure 1 is a longitudinal vertical section through a building, showing
30 my device therein. Fig. 2 is a detail of the drum carrying the paper, &c.; Fig. 3, detail of the speaking-tube end, showing the hinged flap and weighted arm holding the pen.

A A A represent the stories of a building, having speaking-tubes a a a running from each story to an office, B, as is usual in many business-houses, &c. My great improvement is to utilize these tubes or pipes for recording purposes, as follows: The lower end of each
35 speaking-tube is provided with a vertical flap, b, hinged at the bottom to the pipe, thus clos-
ing temporarily that opening, which is addi-
40 tional to the one c, used for speaking and whistling through, which is situated at some
45 convenient part of the tube, as shown in Figs. 1 and 3. The flap b is kept closed by a weight-
ed rod, d'; or a fine spring attached to top of
flap and to the tube may be employed. The
rod d' is elongated into an arm, d'', its end

holding a writing-tube, pencil, or pricking-
50 point, e, as shown. All the mouths of the
speaking-tubes in the office are thus provided,
and these marking devices stand just over a
barrel, C, revolved by ordinary clock-work,
(not shown,) said barrel setting on the hour-
55 hand spindle f thereof, which is made long
enough at the back for that purpose. Around
and over the surface of this barrel is set a pa-
per, D, which is ruled around in as many lines
or spaces left as there are stories or speaking-
60 tubes in the building, each space between the
lines marked off into hours, halves, quarters,
or other subdivisions, as desired, or to corre-
spond with those on a clock-dial.

At, say, 6 o'clock p. m. the clock and bar-
rel are started at that hour. The watchman,
making his rounds, goes to the speaking-tube
in each room or story and blows into the
mouth-piece of the tube in each room. This
throws forward the hinged flap b, and with it
70 the marking device e, which strikes the paper
D on the barrel C, making a dot thereon, as
shown in Fig. 2. The flap is immediately
thrown back by the counter-balance d', which
closes the pipe-opening, ready for the next
75 visit and record. The operation of one is that
of each and all, each pipe having its own re-
cording device held over the paper of the drum,
as explained. The mouth of these tubes a a
80 a, with the flap and pen, the clock-work, and
the usual mouth-pieces and whistle, are all in-
closed in a case, E, which is locked at night
and only opened in the morning for examina-
85 tion by the proper person to see that the spaces
for hours or other subdivisions are marked by
the automatic pen e. The back or side E' of
this case E is hinged and provided inside with
pads or gags, which fit closely into the usual
90 mouth-pieces, c, of the speaking-tubes, so as to
prevent the wind escaping through them or
the record being tampered with by them. In
the day-time this end E' is raised, leaving the
mouth-pieces exposed for their appropriate use.

I claim—

1. In combination with the speaking-tubes
95 a a a of a building, &c., the flap b, hinged to
the mouth of each tube, with an attached arm,
d'', having a recording-instrument, e, at one

end, and provided with a spring or counter-balance, d' , at the other end, all substantially as and for the purpose specified.

2. In combination with the pipes a a , flaps b , arms d' d'' , and pen e , the paper D , divided into time-spaces and set around a drum, C , which is revolved by suitable clock-work, all substantially as and for the purpose set forth.

In witness whereof I have hereunto signed my name in the presence of two subscribing witnesses.

A. B. GOODRICH.
